ROBERT CREUZBAUR, OF NEW YORK, N. Y.

Letters Patent No. 72,170, dated December 17, 1867.

A.

IMPROVEMENT IN BOAT-LOWERING APPARATUS.

The Schedule referred to in these Letters Patent and making part of the same.

TO ALL WHOM IT MAY CONCERN:

Be it known that I, ROBERT CREUZBAUR, of New York city, in the county and State of New York, have invented an Apparatus for Lowering and Picking up Boats; and I do hereby declare that the following is a full, clear, and exact description thereof, reference being had to the accompanying drawings, making a part of this specification, in which—

Figure 1, sheet 1, is a vertical sectional view of a portion of a deck, and one side of a ship, showing, in side elevation, the application thereto of the improved boat-lowering and picking-up apparatus.

Figure 2, sheet 1, is a similar view of the same parts shown in fig. 1, indicating the davits in the act of raising or lowering a boat.

Figure 3 is a vertical diametrical section through one of the davit-springs, enlarged.

Figure 4, sheet 2, is a top view of fig. 2.

Figure 5, sheet 2, is a view, partly in section, of the upper portion of one of the davits.

Similar letters of reference indicate corresponding parts in the several figures.

The object of this invention is to overcome the dangers and difficulties incident to the raising, lowering, and casting off of ships' boats, and to render access to and from a boat comparatively safe. Under the old mode of constructing and arranging the davits from which ships' boats are suspended and lowered, the boats are necessarily brought so near the side of the vessel, that even under ordinary swells of the sea there is great danger of having the boats dashed against the vessel, and capsized or crushed.

To avoid these accidents, the nature of my invention consists in so constructing the davits and applying them to a vessel, that they shall have a free swinging motion toward and from the water, and at the same time admit of being turned around like a crane when they are in upright positions, so that when the boat is not in immediate use, it can be swung inward over the deck of the vessel and lashed fast, as will be hereinafter described.

The invention also consists in the application of springs, or other equivalent means, to davits which are allowed to have a vertically-swinging motion toward and from the water, in such manner that the tendency of the davits shall always be to assume upright positions when unrestrained by the weight of the boat; thus, when a boat is launched, but, moored to the davits, rises upon a wave, the davits will also rise, and thus prevent collision and injury to passengers in the boat, as will be hereinafter described.

To enable others skilled in the art to understand my invention, I will proceed to describe one practical mode of carrying it into effect.

In the accompanying drawings, A A represents two hinged or pivoted davits, which are attached to the outside of the vessel by means of pins, a a, or in any other suitable manner which will admit of the davits being vibrated in vertical planes at right angles to the length of the vessel, as indicated by the two positions shown in figs. 1 and 2. These davits are hinged or pivoted separately to the vessel's side, so that they may have independent movements of each other, or rise and descend in the arc of a circle together.

The drawings represent the lower ends of the davits forked, and pivoted to brackets, which are rigidly fastened to the vessel outside; but it is not contemplated to confine the invention to this peculiar attachment, as other modes of hinging the davits may be adopted. The forked ends of the davits serve to brace and strengthen them, and prevent vibration and undue strain in a direction with the length of the vessel. The upper ends of the standards or straight portions of the davits A A are constructed with sockets in them, in which screw-threads are formed, for receiving the screw-threaded lower ends of the curved overhanging portions of the davits, from which the boat B is suspended. This mode of constructing the davits will allow of the swinging of their curved top portions or sections, with boat attached, inward or over the deck of the vessel, as indicated by red lines in fig. 1, in which figure the curved portions of the davits are also represented as turned outward. At the extremity of the curved part of each davit is a pulley, P, over which the suspending-rope R works, and upon which this rope is safely held by the shield S, which turns freely on the axle of said pulley, so as to conform to the different positions or directions of the rope in raising and lowering the free end of the davit. This shield S has an eye, b, through which rope R passes, and by which the hood or shield is caused to accommodate itself to this rope, and also held safely in the groove of the pulley P, whether the boat surges fore and aft, or in any other direction.

To enable a person to pass safely down over the davit or davits to a boat which is lowered in the water, or to pass from such boat to the vessel, a ladder or stairway is constructed upon both the straight and curved sections of each davit. This may be done by screwing rounds $r^1 r^2$ into the sides of the straight and curved sections of the davits, and applying rails $r^1 r^2$ to the ends of said rounds, as shown in fig. 4, sheet 2. In the model, the rounds and rails of the curved sections of the davits are applied on the inner sides thereof, while the rounds and rails of the straight sections are applied on their outer sides; it would be preferable, however, to place the latter on the inside also. In order to complete the passage-way, a hand-railing is applied to each section of each davit, which railing is formed on the straight portion of each davit by the supporting-standards $d d$, and rail c . These standards are pivoted to the rounds, or to ears at one end, and to the rail c at the other end. The rail c is hinged by its lower or inner end at c' to one of the suspension-bars V , above the point of attachment of the davit to the vessel's side, and all the parts are of such length that true parallelograms are formed between the several pivots, which admit of said parts folding up compactly when the davit is brought to an upright position, shown in fig. 1. On the curved portion of each davit, the hand-rail consists simply of a standard, u , with a hand-rope, d^1 , fastened to an eye on the free end of the rail e , and passing through an eye formed on the upper end of this standard, as well as through an eye at the outer extremity of the rail r^2 , terminating in a ball or float, d^2 , to keep it taut, and to facilitate the grasping of this rope. The weight of the boat will prevent the turning of these curved portions when stepped upon by persons. When the ladder-ways on the upper and lower portions are both on the inside, the former lap and rest on the latter, which steadies them the more. The rope R of each davit passes from the hooded pulley P over a pulley, F , figs. 1 and 2, and thence down the gunwale, beneath the deck of the vessel, and under a pulley, G . From this pulley the rope of each davit passes beneath a pulley, h , to a drum, k . The rope R of each davit is prevented from fouling by having a grooved roller, h' , to press upon it and hold it securely in its place in the groove of the pulley h . The drums $K K$ are applied to a shaft, L , which is arranged longitudinally with and in the centre of the vessel, as shown in fig. 4, sheet 2. By means of a friction-brake, a hand-wheel, and a ratchet and pawl, applied to the drum-shaft L , one person can raise and lower a boat on an even keel. Those parts which relate to the drums and the method of rigging the boat and davits, will be described in another application for a patent, which I have lettered "B," and which will accompany this application.

As the vibrating davits, when lowered, would endanger a boat rising suddenly upon a wave, it is desirable to have these davits rise out of the way of the boat when relieved of the weight thereof. For this purpose, two suspension-bars, $V V$, are hinged to each davit, close to their respective pivots, as shown in figs. 1 and 2. The upper ends of each pair of bars $V V$ are pivoted to the outer forked ends of the lever X , which has its fulcrum in the side of the vessel. The inner end of this lever X is pivoted to the upper end of the rod Y , which passes down through a series or pile of springs, I , which are made of India rubber or other suitable material, and which alternate with plates I' . These springs are confined between cap and bottom plates, in a suitable manner, and upon said rod Y , beneath the bottom-plate, a screw-nut, Y' , is applied, by which the tension of the springs can be easily regulated. The cap-plate is confined by two outside rods to the fixed bracket Z , as shown. The lower end of the said rod Y passes freely through an eye which is made through the said fixed bracket Z , so that this rod, with its springs, will accommodate itself to the sweep of the end of lever X , and the davits will preserve a proper distance from a floating boat suspended from them. When the davits are both brought to upright positions, shown in fig. 1, and secured by means of latches, g , or other suitable device, their upper curved sections may be swung around like the old and well-known swinging davits, and under certain circumstances a boat may be raised and lowered in the usual manner, without swinging the davits toward and from the water.

The devices for attaching the boat to the ends of the davit-ropes $R R$, and detaching it therefrom, may be constructed in any suitable manner. The device shown in the drawings will answer a very good purpose, and will form the subject of an application for a patent, which is lettered "C," and which will accompany this application.

Having described my invention, what I claim as new, and desire to secure by Letters Patent, is—

1. Davits which are hinged in such manner as to swing freely in vertical or nearly vertical planes toward and from the water, and to vibrate above and below a horizontal plane intersecting their axes of motion, substantially as described.
2. The application of curved sections to the upper ends of davits which are hinged at their lower ends, so that said sections can be turned around, independently of the standards or lower sections of the davits, substantially as described.
3. The application of a ladder to a davit, operating substantially as described.
4. The combination of a folding hand-rail and ladder to a hinged davit, operating substantially as described.
5. Boats' davits, hinged substantially as described, when counterpoised by a force sufficient to raise them without the boat, but easily overcome by the weight of the boat.
